UNITED STATES PATENT OFFICE.

JOHN E. KENNEDY, OF BOSTON, MASSACHUSETTS.

DESIGN FOR SHOE-SOLE FABRIC.

SPECIFICATION forming part of Design No. 32,416, dated March 27, 1900.

Application filed February 23, 1900. Serial No. 6,310. Term of patent 14 years.

To all whom it may concern:

Be it known that I, JOHN E. KENNEDY, a subject of the Queen of Great Britain, residing at Boston, in the county of Suffolk and State of Massachusetts, have invented and produced a certain new and original Design for Shoe-Sole Fabric, of which the following is a specification, reference being had to the accompanying drawings, forming a part thereof.

Figure 1 of the drawings is a perspective view of a portion of fabric, illustrating my design. Fig. 2 is a cross sectional view thereof on the line x , and Fig. 3 is a sectional view taken longitudinally of the ribs.

The leading feature of my design consists in a fabric having a central web or integument provided with parallel ribs or ridges projecting from opposite sides thereof, the ribs on one side being located opposite the space between the ribs on the other side, the ribs being rectangular in cross-section, with

correspondingly - shaped grooves therebetween.

The web or integument a is provided with ribs or ridges b , on opposite sides thereof, rectangular in cross-section, the ribs on one side being located opposite the spaces or grooves b^x between the ribs on the other side of the web, the grooves being shaped correspondingly to the ribs and of like width and depth. 25 30

Having fully described my design, what I claim, and desire to secure by Letters Patent, is—

The design for a shoe-sole fabric, substantially as herein shown and described. 35

In testimony whereof I have signed my name to this specification in the presence of two subscribing witnesses.

JOHN E. KENNEDY.
